RECEPTACLE FOR TABLEWARE
AND THE LIKE

Morris I. Naken, Chicago, Ill.

Application June 20, 1947, Serial No. 755,915

2 Claims. (Cl. 217—3)

1

This invention relates to improvements in storage receptacles for tableware and the like, and more particularly to receptacles designed to receive and store sterling silver or silver plated table flatware and which are commonly known as silver chests.

It is common practice for the householder to store the sterling silver or silver plated table flatware in such silver chests which are receptacles or containers specifically designed to receive and retain such articles. The principal and serious fault of the present commercial chest is that when the flatware is most urgently required it is found to be in a tarnished condition requiring the expenditure of time and effort for washing and polishing before it can be used. This is especially true in the inexpensive or medium priced field.

It is a well known fact that tarnish is caused principally by the sulphur in the atmosphere which combines with the silver to form a silver sulphide deposit upon the flatware. Some tarnish too is caused by oxidation.

Various expedients have been tried to overcome this undesirable condition and make the silver chest tarnish proof but without success. The ordinary or standard commercial chest when closed readily admits air and the custom chest is very expensive with a limited market. The industry has apparently despaired of making an inexpensive airtight container and the method commonly resorted to at the present time is the use of a specially prepared cloth as a chest lining. By a well known process, silver particles are deposited throughout such cloth area it being expected that such silver particles would take up a sufficient amount of the atmospheric sulphur to prevent a silver sulphide deposit on the flatware. Such specially prepared lining is expensive and has failed to achieve the intended purpose.

Another common expedient is to lacquer the individual pieces but after a short period of use the lacquer is destroyed. Repeated lacquering is both expensive and bothersome and is soon abandoned.

It is the object of the present invention to provide a new and improved silver chest which is free from the faults of the prior art.

A further object is to provide a silverware chest which is relatively airtight and which will store silverware for an indefinite period without tarnish.

A further object is to provide a silverware chest which can be made in quantity for the retail trade and which is sufficiently airtight to keep the stored articles in bright condition.

2

Another object is to provide a silverware chest which may contain a number of relatively hermetically sealed compartments in the chest.

Another object is to provide a silverware chest which can be cheaply and inexpensively made, which is both appealing in appearance and relatively airtight to prevent tarnish.

These and numerous other objects and advantages will be apparent throughout the progress of the following specifications.

The accompanying drawing illustrates a selected embodiment of the invention and the views therein are as follows:

Fig. 1 is a perspective view of the improved 15 silver chest.

Fig. 2 is a cross sectional view taken on line 2—2 of Fig. 1.

Figure 3 is a front view showing the depending portion of the cover turned back.

20 Fig. 4 is an enlarged fragmentary front end view.

To illustrate the preferred embodiment of the present invention there is shown a chest 2 comprising a container body 10 of any desired size and shape having a base 12, side walls 14, rear wall 16 and the front wall 18. The base and walls are constructed of rigid material 20 and covered on their outer faces with the covering material 22. It has been found that when rigid fibrous material such as wood is used for container body construction satisfactory results are obtained, such material supplying sufficient rigidity with lightness of weight. Leather, Leatherette, or any similar substance may be employed as a suitable covering material.

35 The inner faces and wall edges of said container body 10 are covered with felted material 24 to prevent scratching and marring the surfaces of the silverware and for other reasons hereinafter to be explained. The outer face of front wall 18 is also covered in whole or in part with the similar felted material 26 as shown in Fig. 3. The felting of the outer face of front wall 18 is of paramount importance for reasons hereinafter

40 shown.

45 Permanently secured and sealed across the rear wall 16 of container body 10 in any well known manner is the cover 28 preferably of a flexible construction and which may be made of the same material as that used in covering the outer faces of said container body 10 or any other material as desired. The cover 28 is lined on its inner face with felted material 30 and is made sufficiently long to impend over the felted edge 50 of the front wall 18 and the felted portion 26 thereof to form a depending portion 32 as shown

in Fig. 4. When the chest is closed, a portion of the felted material 30 of the cover 28 is always in close contact with the felted edge and felted outer face of front wall 18 as shown at 33 in Fig. 3. A weighted member 34 is enclosed in the front edge of cover 28 which causes the depending portion 32 of said cover to hug the front wall of said container body 10 and to maintain close contact between the felted areas of the cover and the said front wall.

The hair particles of such felted areas have a mechanical affinity for each other and the friction arising out of the contact between the two felted surfaces creates an electrostatic field which causes the said hair particles in such areas where contact is maintained to interlock and intertwine thus forming an air seal which prevents the ingress of any substantial amount of air into the chest.

The cover 28 is further formed along each side with slide fasteners 36 which lock and seal the said cover to the side walls 14 of container body 10 so that when closed the chest becomes a relatively hermetically sealed, airtight container.

If desired the chest 2 may be constructed with one or more partitioning members 38 and of a height substantially equal to the height of the container walls said partitioning members being covered on all its outer faces with felted material 40. It will be apparent that when so constructed individual airtight compartments such as 42 are formed inside the chest 2 the felted inner facing cover material 30 combining with the welted partitioning members as at 42 to create a positive inner seal thus further preventing the ingress of air into the sealed compartment.

It may be noted that a flexible cover is employed and slide fasteners are used as locking means in the preferred embodiment of the invention. Although such construction has been found to be very satisfactory, the conventional rigid or semi-rigid cover may be used in conjunction with any other well known locking means without departing from the spirit of the invention. It has been further found that when the principle of using a felted lining on the cover in combination with felted outer walls and edges is employed satisfactory results are obtained even though all other locking or sealing means are dispensed with.

Any type of felted material may be used to line the cover and the walls and edges of the container body 10 with satisfactory results but if the specially treated felt such as hereinabove described is used silver or silver plated tableware may be kept in the improved chest almost indefinitely without tarnishing.

It may be noted that although rigid filamentary or fibrous material such as wood is preferred as material for constructing the container body 10 and partitioning members 38, any type of rigid material including metal may be used without losing the advantages imparted by the invention.

It thus may be seen that the present invention provides a relatively airtight, hermetically sealed silverware chest which may be easily and cheaply manufactured and yet which retains and stores the silver tableware in sealed compartments substantially preventing tarnishment.

Changes may be made in form and construc-

tion without departing from the spirit of the inventions or sacrificing any of the advantages and the right is hereby reserved to make all changes as fairly fall within the scope of the following claims.

What is claimed as new and desired to be secured by Letters Patent of the United States is as follows.

I claim:

- 10 1. A relatively airtight receptacle for tableware and the like comprising an open top rigid walled container body having a front wall partially felted on its outer face, a flexible cover for said container body permanently secured to the rear wall of said container body, said cover having a felted inner face and being of sufficient length to impend over the partially felted outer face of the front wall of said container body, the felted surfaces of the cover and the outer face of the front wall being in juxtaposition when the receptacle is closed, slide fastening opening and closing means along the sides of said container body and cover for opening and closing said receptacle and a weighted member enclosed in the front edge of said cover to retain the depending portion of said cover in contact with the front wall of said receptacle whereby felted portions of the cover and the front wall are kept in constant juxtapositive position when the receptacle is closed.
- 15 2. A relatively airtight chest for tableware and the like comprising a substantially rectangular open top rigid walled container body, said container body being substantially felted on its inner surfaces and walls and having a front wall partially felted on its outer face, a plurality of felted partitioning members in said container body at least one of which partitioning members in said container body is of a height substantially equal to the height of said container walls, a flexible cover for said container body permanently secured to the rear wall of said container body said cover having a felted inner face and being of a sufficient length to impend over the partially felted outer face of the front wall of said container body, the felted surfaces of the cover and the outer face of the front wall being in juxtaposition when receptacle is closed, slide fastening opening and closing means along the sides of said container body and cover for opening and closing said chest and a weighted member enclosed in the front edge of said cover to retain the depending portion of said cover in contact with the front wall of said chest whereby felted portions of the cover and front wall are kept in constant juxtapositive position when the chest is closed.
- 20 3. A relatively airtight chest for tableware and the like comprising a substantially rectangular open top rigid walled container body, said container body being substantially felted on its inner surfaces and walls and having a front wall partially felted on its outer face, a plurality of felted partitioning members in said container body at least one of which partitioning members in said container body is of a height substantially equal to the height of said container walls, a flexible cover for said container body permanently secured to the rear wall of said container body said cover having a felted inner face and being of a sufficient length to impend over the partially felted outer face of the front wall of said container body, the felted surfaces of the cover and the outer face of the front wall being in juxtaposition when receptacle is closed, slide fastening opening and closing means along the sides of said container body and cover for opening and closing said chest and a weighted member enclosed in the front edge of said cover to retain the depending portion of said cover in contact with the front wall of said chest whereby felted portions of the cover and front wall are kept in constant juxtapositive position when the chest is closed.
- 25 4. A relatively airtight chest for tableware and the like comprising a substantially rectangular open top rigid walled container body, said container body being substantially felted on its inner surfaces and walls and having a front wall partially felted on its outer face, a plurality of felted partitioning members in said container body at least one of which partitioning members in said container body is of a height substantially equal to the height of said container walls, a flexible cover for said container body permanently secured to the rear wall of said container body said cover having a felted inner face and being of a sufficient length to impend over the partially felted outer face of the front wall of said container body, the felted surfaces of the cover and the outer face of the front wall being in juxtaposition when receptacle is closed, slide fastening opening and closing means along the sides of said container body and cover for opening and closing said chest and a weighted member enclosed in the front edge of said cover to retain the depending portion of said cover in contact with the front wall of said chest whereby felted portions of the cover and front wall are kept in constant juxtapositive position when the chest is closed.
- 30 5. A relatively airtight chest for tableware and the like comprising a substantially rectangular open top rigid walled container body, said container body being substantially felted on its inner surfaces and walls and having a front wall partially felted on its outer face, a plurality of felted partitioning members in said container body at least one of which partitioning members in said container body is of a height substantially equal to the height of said container walls, a flexible cover for said container body permanently secured to the rear wall of said container body said cover having a felted inner face and being of a sufficient length to impend over the partially felted outer face of the front wall of said container body, the felted surfaces of the cover and the outer face of the front wall being in juxtaposition when receptacle is closed, slide fastening opening and closing means along the sides of said container body and cover for opening and closing said chest and a weighted member enclosed in the front edge of said cover to retain the depending portion of said cover in contact with the front wall of said chest whereby felted portions of the cover and front wall are kept in constant juxtapositive position when the chest is closed.
- 35 6. A relatively airtight chest for tableware and the like comprising a substantially rectangular open top rigid walled container body, said container body being substantially felted on its inner surfaces and walls and having a front wall partially felted on its outer face, a plurality of felted partitioning members in said container body at least one of which partitioning members in said container body is of a height substantially equal to the height of said container walls, a flexible cover for said container body permanently secured to the rear wall of said container body said cover having a felted inner face and being of a sufficient length to impend over the partially felted outer face of the front wall of said container body, the felted surfaces of the cover and the outer face of the front wall being in juxtaposition when receptacle is closed, slide fastening opening and closing means along the sides of said container body and cover for opening and closing said chest and a weighted member enclosed in the front edge of said cover to retain the depending portion of said cover in contact with the front wall of said chest whereby felted portions of the cover and front wall are kept in constant juxtapositive position when the chest is closed.
- 40 7. A relatively airtight chest for tableware and the like comprising a substantially rectangular open top rigid walled container body, said container body being substantially felted on its inner surfaces and walls and having a front wall partially felted on its outer face, a plurality of felted partitioning members in said container body at least one of which partitioning members in said container body is of a height substantially equal to the height of said container walls, a flexible cover for said container body permanently secured to the rear wall of said container body said cover having a felted inner face and being of a sufficient length to impend over the partially felted outer face of the front wall of said container body, the felted surfaces of the cover and the outer face of the front wall being in juxtaposition when receptacle is closed, slide fastening opening and closing means along the sides of said container body and cover for opening and closing said chest and a weighted member enclosed in the front edge of said cover to retain the depending portion of said cover in contact with the front wall of said chest whereby felted portions of the cover and front wall are kept in constant juxtapositive position when the chest is closed.
- 45 8. A relatively airtight chest for tableware and the like comprising a substantially rectangular open top rigid walled container body, said container body being substantially felted on its inner surfaces and walls and having a front wall partially felted on its outer face, a plurality of felted partitioning members in said container body at least one of which partitioning members in said container body is of a height substantially equal to the height of said container walls, a flexible cover for said container body permanently secured to the rear wall of said container body said cover having a felted inner face and being of a sufficient length to impend over the partially felted outer face of the front wall of said container body, the felted surfaces of the cover and the outer face of the front wall being in juxtaposition when receptacle is closed, slide fastening opening and closing means along the sides of said container body and cover for opening and closing said chest and a weighted member enclosed in the front edge of said cover to retain the depending portion of said cover in contact with the front wall of said chest whereby felted portions of the cover and front wall are kept in constant juxtapositive position when the chest is closed.
- 50 9. A relatively airtight chest for tableware and the like comprising a substantially rectangular open top rigid walled container body, said container body being substantially felted on its inner surfaces and walls and having a front wall partially felted on its outer face, a plurality of felted partitioning members in said container body at least one of which partitioning members in said container body is of a height substantially equal to the height of said container walls, a flexible cover for said container body permanently secured to the rear wall of said container body said cover having a felted inner face and being of a sufficient length to impend over the partially felted outer face of the front wall of said container body, the felted surfaces of the cover and the outer face of the front wall being in juxtaposition when receptacle is closed, slide fastening opening and closing means along the sides of said container body and cover for opening and closing said chest and a weighted member enclosed in the front edge of said cover to retain the depending portion of said cover in contact with the front wall of said chest whereby felted portions of the cover and front wall are kept in constant juxtapositive position when the chest is closed.
- 55 10. A relatively airtight receptacle for tableware and the like comprising an open top rigid walled container body having a front wall partially felted on its outer face, a flexible cover for said container body permanently secured to the rear wall of said container body, said cover having a felted inner face and being of sufficient length to impend over the partially felted outer face of the front wall of said container body, the felted surfaces of the cover and the outer face of the front wall being in juxtaposition when receptacle is closed, slide fastening opening and closing means along the sides of said container body and cover for opening and closing said receptacle and a weighted member enclosed in the front edge of said cover to retain the depending portion of said cover in contact with the front wall of said receptacle whereby felted portions of the cover and the front wall are kept in constant juxtapositive position when the receptacle is closed.
